UNITED STATES PATENT OFFICE.

OSCAR T. LARSEN, OF SAN FRANCISCO, CALIFORNIA.

FURNITURE GLIDER SHOE.

Application filed September 26, 1925. Serial No. 58,882.

My invention relates to improvements in glider shoes for furniture legs and the like wherein a floor engaging element, adapted to provide a relatively large supporting surface and to reduce friction when moved along a floor, is resiliently held in spaced relation to the bottom of a furniture support.

The primary object is to provide an improved glider shoe for furniture legs.

Another object is to provide an improved glider shoe for furniture which will reduce wear and disfigurement of floors when furniture is moved thereover.

15 A further object is to provide an improved device of the character described which may be easily applied, and which is attractive in appearance, and efficient in operation.

20 A further object is to provide an improved device providing an effective resilience between the floor and the furniture.

25 A still further object is to provide an improved construction which will be simple in construction and installation and which will be very durable in service.

I accomplish these and other objects by means of the improved device disclosed in the drawings forming a part of the present specification wherein like characters of reference are used to designate similar parts throughout said specification and drawings and in which,

30 Fig. 1 is a vertical section of my improved glider shoe as applied upon the bottom of a furniture supporting leg.

35 Fig. 2 is a plan view, partly in section, of my improved glider shoe.

Fig. 3 is a vertical section of the floor engaging member and the mounting element 40 showing the manner in which the same are assembled.

Fig. 4 is a vertical section showing the manner in which the glider shoe may be applied without the resilient supporting member when desired.

Referring to the drawings the numeral 1 is used to designate in general a floor engaging member provided with an upwardly turned annular flange 2. The bottom of the 50 member 1 is lightly arched, the arc of said bottom being of a long radius so that a relatively large supporting surface will be formed.

Within the floor engaging member 1 is 55 mounted a mounting element 3 provided with an annular flange 4 arranged to fit

closely within the flange 2. The center of the mounting member 3 is pressed to form a raised center portion 6 forming a recess 7 between the member 3 and the bottom of 60 the floor engaging member 1, said recess being preferably made square to receive the squared head 8 of a screw or other suitable securing member 9 extending outwardly through an aperture 11 formed in the center 65 of the raised portion.

The corners of the square raised portion 9 are spaced from the edges of the flanges 2 and 4 to receive a ring 12 of rubber or other suitable resilient material. The ring 12 is 70 held firmly between the corners of said raised portion 9 and said flanges and extends upwardly above the upper edges thereof to form a cushion and to hold the members 1 and 2 in spaced relation to the bottom 75 of a furniture supporting leg 14.

The glider shoe is applied by securing the securing member 9 onto the bottom of the leg 14. In the form of securing member illustrated, the member 9 is screwed into 80 the bottom of the leg. The square raised portion 6 engages the head 8 of the securing means and prevents rotation of the shoe upon the securing member, thereby permitting the securing member to be screwed into 85 the leg by means of the shoe without the use of a wrench or other tool.

The square center portion 6 is made of sufficient depth to permit a limited sliding movement of the head 8 therein, said sliding 90 movement permitting the ring 12 to be compressed to varying degrees between the shoe and the bottom of the leg 14.

In operation, the shoe is applied as above explained, the ring 12 being held firmly between the mounting member 3 and the bottom of the leg 14 and forming a resilient support for the furniture. The slightly arched bottom surface of the member 1 is polished and offers a very low resistance to a sliding movement of the shoe over the floor, the low frictional resistance permitting the furniture to be easily moved from place to place over the floor. At the same time, the long radius of curvature of the floor engaging surface affords a relatively large area of contact between the shoe and the floor, thereby distributing the weight of the furniture over an area sufficiently large to prevent the denting of the floor under the shoe. 100 105

The resilient ring upon which the weight of the furniture is supported absorbs vibra-

tion and forms a cushion adapted to absorb shock due either to the sudden application of a weight upon the furniture or to the dropping of the furniture itself, this cushion action serving to protect the floor from being dented, as such shock is absorbed by the ring rather than being communicated directly to the floor.

The structure illustrated is particularly useful because of its simplicity because of its economy and durability. The members 1 and 3 are initially shaped with the flanges 2 and 4 straight. The securing member is inserted through the aperture 11 and the members 1 and 3 then assembled in the relation indicated in Fig. 3 of the drawings. The edges of the flanges are subsequently pressed inwardly so that the mounting member is rigidly crimped within the member 1 and held in assembled relation therewith. The rounded edge of the assembled shoe presents an inconspicuous but attractive appearance.

The resilient ring 12 is a relatively heavy solid band of rubber upon which the weight of the furniture is supported and which affords a relatively large supporting surface. The ring is not subject to any stress other than the compressive stress due to the weight of the furniture supported thereon. There is therefore substantially no wear upon the ring and it need only be replaced after long service when the rubber has lost its resiliency through age.

In addition to the cushioning effect of the ring 12, it serves the further purpose of accommodating the shoe to legs arranged at a slight angle from the vertical. Thus if the leg is arranged at a slight angle, as indicated in dotted lines in Fig. 1, the rubber ring will be compressed to a greater extent upon the inner side of the leg and the shoe allowed to assume its normal relation to the floor. This feature, combined with the long radius of curvature of the member 1 permits the shoe to be applied to legs arranged at any ordinary angle without impairing the efficiency or altering the manner in which the shoe is applied, the wide supporting surface of the member 1 being adapted to give the desired area and low frictional resistance regardless of the inclination of the leg to which it is applied.

If desired, the shoe may be applied without the resilient ring 12, as shown in Fig. 4 of the drawings. The structure and the method of applying the shoe is the same as above described except that the ring is omitted when the shoe is secured to the bottom of the leg 14 and the securing member advanced until the edge of the flange 2 engages the bottom of the leg. In this manner the same efficient supporting surface and ease of movement is obtained and only the resiliency is sacrificed.

Having thus described my invention what I claim as new and desire to secure by Letters Patent is,

1. A glider shoe for furniture legs comprising a floor engaging member; a mounting element mounted within said member; a securing element directly and loosely engaging the mounting element and adapted to be secured upon the bottom of a furniture supporting leg; and a resilient ring carried by the mounting element and held against the bottom of the leg to resiliently support said leg above the floor engaging member. 70

2. A glider shoe for furniture legs comprising a floor engaging member; a mounting element mounted within said member; a securing element mounted in slidable engagement with the mounting element and adapted to be secured upon the bottom of a furniture supporting leg; and a resilient ring carried by the mounting element and held against the bottom of the leg to resiliently support said leg above the floor engaging member. 80

3. A glider shoe for furniture legs comprising a floor engaging member; a mounting element mounted within said member and provided with a raised center portion; and a securing element slidably engaging the raised center portion and adapted to be secured to the bottom of a furniture supporting leg. 90

4. A glider shoe for furniture legs comprising a floor engaging member; a mounting element mounted within said member and provided with a raised center portion; and a securing element slidably engaging the raised center portion and adapted to be secured to the bottom of a furniture supporting leg; and a resilient weight supporting element held between the mounting member and the bottom of the leg to resiliently support said leg. 100

5. A glider shoe for furniture legs comprising a floor engaging member; a mounting element mounted within said member and provided with a raised center portion forming a recess between said mounting element and the floor engaging member; and a securing element provided with a head slidably engaged within the recess and adapted to be secured upon the bottom of a furniture supporting leg. 110

6. A glider shoe for furniture legs comprising a floor engaging member; a mounting element mounted within said member and provided with a raised center portion forming a recess between said mounting element and the floor engaging member; and a securing element provided with a head slidably engaged within the recess and adapted to be secured upon the bottom of a furniture supporting leg; and a resilient ring mounted within the mounting element around the raised portion and extending up- 120

- wardly above said raised portion, said ring being held against the bottom of the leg to resiliently support the leg above the floor engaging member.
7. A glider shoe for furniture legs comprising a floor engaging member; a mounting element mounted within said member and provided with a raised center portion shaped to form a square recess between said mounting element and the floor engaging member; and a securing element provided with a square head slidably engaged within the recess and adapted to be secured upon the bottom of a furniture supporting leg.
10. A glider shoe for furniture legs comprising a floor engaging member; a mounting element mounted within said member and provided with a raised center portion shaped to form a square recess between said mounting element and the floor engaging member; and a securing element provided with a square head slidably engaged within the recess and adapted to be secured upon the bottom of a furniture supporting leg.
15. 8. A glider shoe for furniture legs comprising a floor engaging member; a mounting element mounted within said member and provided with a raised center portion shaped to form a square recess between said mounting element and the floor engaging member; and a securing element provided with a square head slidably engaged within the recess and adapted to be secured upon the bottom of a furniture supporting leg;
20. 9. A glider shoe for furniture legs comprising a floor engaging member having an upwardly turned annular flange; a mounting element mounted within the floor engaging member, said element having an annular flange fitting closely within the flange formed upon the member and held in engagement therewith by curving said flanges inwardly about a common axis; a square raised center portion formed upon the mounting element, said portion forming a recess between the mounting element and the floor engaging member and having its outer surfaces spaced from the edges of the annular flanges; and a securing element provided with a square head slidably mounted within the recess and adapted to be secured upon the bottom of a furniture supporting leg; and a resilient ring mounted within the mounting element around the raised portion thereof and extending above said raised portion, said ring being held against the bottom of the leg to resiliently support the leg above the floor engaging member.
25. 10. A glider shoe for furniture legs comprising a floor engaging member having an upwardly turned annular flange; a mounting element mounted within the floor engaging member, said element having an annular flange fitting closely within the flange formed upon the member and held in engagement therewith by curving said flanges inwardly about a common axis; a square raised center portion formed upon the mounting element, said portion forming a recess between the mounting element and the floor engaging member and having its outer surfaces spaced from the edges of the annular flanges; and a securing element provided with a square head slidably mounted within the recess and adapted to be secured upon the bottom of a furniture supporting leg; and a resilient rubber ring mounted within the mounting member and held between the raised center portion and the flanges, said ring extending upwardly above the center portion and engaging the bottom of the leg to hold the floor engaging member in spaced relation to the bottom of the leg and to resiliently support the weight of the furniture.
30. 11. A glider shoe for furniture legs comprising a floor engaging member having an upwardly turned annular flange; a mounting element mounted within the floor engaging member, said element having an annular flange fitting closely within the flange formed upon the member and held in engagement therewith by curving said flanges inwardly about a common axis; a square raised center portion formed upon the mounting element, said portion forming a recess between the mounting element and the floor engaging member and having its outer surfaces spaced from the edges of the annular flanges; and a securing element provided with a square head slidably mounted within the recess and adapted to be secured upon the bottom of a furniture supporting leg; and a resilient rubber ring mounted within the mounting member and held between the raised center portion and the flanges, said ring extending upwardly above the center portion and engaging the bottom of the leg to hold the floor engaging member in spaced relation to the bottom of the leg and to resiliently support the weight of the furniture.
35. 12. A glider shoe for furniture legs comprising a floor engaging member having an upwardly turned annular flange; a mounting element mounted within the floor engaging member, said element having an annular flange fitting closely within the flange formed upon the member and held in engagement therewith by curving said flanges inwardly about a common axis; a square raised center portion formed upon the mounting element, said portion forming a recess between the mounting element and the floor engaging member and having its outer surfaces spaced from the edges of the annular flanges; and a securing element provided with a square head slidably mounted within the recess and adapted to be secured upon the bottom of a furniture supporting leg; and a resilient rubber ring mounted within the mounting member and held between the raised center portion and the flanges, said ring extending upwardly above the center portion and engaging the bottom of the leg to hold the floor engaging member in spaced relation to the bottom of the leg and to resiliently support the weight of the furniture.
40. 13. A glider shoe for furniture legs comprising a floor engaging member having an upwardly turned annular flange; a mounting element mounted within the floor engaging member, said element having an annular flange fitting closely within the flange formed upon the member and held in engagement therewith by curving said flanges inwardly about a common axis; a square raised center portion formed upon the mounting element, said portion forming a recess between the mounting element and the floor engaging member and having its outer surfaces spaced from the edges of the annular flanges; and a securing element provided with a square head slidably mounted within the recess and adapted to be secured upon the bottom of a furniture supporting leg; and a resilient rubber ring mounted within the mounting member and held between the raised center portion and the flanges, said ring extending upwardly above the center portion and engaging the bottom of the leg to hold the floor engaging member in spaced relation to the bottom of the leg and to resiliently support the weight of the furniture.

In witness whereof I hereunto set my signature.
